UNITED STATES PATENT OFFICE.

STANLEY B. URBANOWITZ, OF CHICAGO, ILLINOIS, ASSIGNOR TO AMERICAN ENVELOPE COMPANY, OF CHICAGO, ILLINOIS, A CORPORATION OF ILLINOIS.

MACHINE FOR ATTACHING STRING FASTENERS TO ENVELOPES.

Application filed April 14, 1922. Serial No. 552,657.

To all whom it may concern:

Be it known that I, STANLEY B. URBANOWITZ, a citizen of the United States, residing at Chicago, in the county of Cook and State of Illinois, have invented a new and useful Improvement in Machines for Attaching String Fasteners to Envelopes, of which the following is a specification.

My invention relates to an improved machine for attaching string fasteners to envelopes of the class in which a string is secured either to the body or flap of an envelope and provided with receiving devices such as a disk or washer on the other portion of the envelope. My invention relates to providing an improved means for feeding the string to and through the disk or washer forming a part of the means for fastening the string to one part of the envelope as distinguished from machines which feed the string to or around the eyelet commonly employed as a part of the string securing means. By my invention I provide a member movable between the punch and die used to set the eyelet and away from said position after feeding the string to permit the punch and die to operate. The movable member referred to, which preferably is in the form of an oscillatory arm, carries devices adjacent the string delivery end of the movable member for positively feeding the string from the movable member and through a perforation in the strip of material from which the retaining washer or disk is subsequently punched, after which the end of the string projecting through said perforation is engaged by a gripper for holding the end of the string in the perforation while the movable member begins its movement away from the path of the punch and die used to set the eyelet. The gripper retains the end of the string but momentarily and then simultaneously with a delay in the movement of the movable member away from the punch and die, the gripper opens to permit the punch to engage the string in the perforation, to force an eyelet through the perforation clamping the string between the eyelet and the washer blank and punch the washer from the washer strip after which the punch carries the washer and eyelet and the engaged end of the string to the envelope and forces the eyelet through the envelope and preferably through a reinforcing washer or disk on the other side of the envelope against the die cooperating with the punch to set the eyelet and fasten the washers and string securely to the envelope. The movable member preferably carries a pivoted delivery device or nozzle which, at the end of the motion of said member to its string delivering position, is turned by the latter part of said motion to enter the die cooperating with the punch to cut the eyelet washer from the washer strip, to thus present the end of the string directly to the perforation in the washer strip before the feeding of the string is begun. This insures positive operation of the mechanism and the positive directing of the string to a position to be engaged by the gripper. By my invention I also provide operating mechanism to properly time the movement of the several parts referred to and I provide devices to cooperate in the handling of the eyelets and washers as will best be understood by reference to the detailed description below of the machine. I prefer to provide in my machine complete perforating and punching mechanism for not only attaching the string and string retaining washer and eyelet to the envelope as described but also at the same time to secure to the other portion of the envelope by means of an eyelet, a similarly formed washer to receive the loose end of the string when it is desired to close the envelope by means of the string. After the string is securely engaged by the eyelet and washer, the movable member is moved to the end of its back travel to provide the desired length of string from the eyelet and washer and then suitable cutting devices are operated to clip the string adjacent the delivery end of the movable member leaving the movable member in readiness to be moved forwardly to provide the next envelope with a string. In my machine I prefer to operate all of the mechanism from a single operating shaft, independent cam mechanism being provided for actuating each of the devices cooperating in handling the string and other parts, which operating shaft is preferably clutch controlled so that the operator by releasing the clutch permits the operating shaft to make one rotation which moves all of the mecha-

nism through the complete cycle of its operation.

My invention will best be understood by reference to the accompanying drawings showing a preferred embodiment thereof in which—

Fig. 1 shows my machine in front elevation, parts of the machine being shown in section to more clearly illustrate the relation of the parts, with the movable member in its string feeding position,

Fig. 2 shows my complete machine in plan view with the movable member in the same position as in Fig. 1, parts of the machine being shown in section to better illustrate the relation of the parts,

Fig. 3 is a sectional view of the parts shown in Figs. 1 and 2 to an enlarged scale along the line 3—3 in Fig. 2 which shows the movable member, the string feeding devices and the parts used to operate the movable member,

Fig. 4 is a sectional view of the parts shown in Fig. 2 to an enlarged scale taken along the line 4—4, and shows the string gripper and the cam mechanism employed to operate it,

Fig. 5 is a sectional view of the parts shown in Fig. 2 to an enlarged scale taken along the line 5—5, and shows the actuating mechanism for the string feeding devices,

Fig. 6 is a sectional view to an enlarged scale taken along the line 6—6 in Fig. 2, and shows the cutting mechanism and its operating devices for cutting the string attached to the envelope,

Fig. 7 is a sectional view of the cam mechanism shown in Fig. 4 taken along the line 7—7,

Fig. 8 is a rear elevation of the parts shown in Fig. 6, taken parallel with the plane of the cutting devices to clearly show their construction and operation,

Fig. 9 shows in a view similar to Fig. 2 to an enlarged scale the string feeding devices in their string feeding position, and the relation of the same to the punching and eyelet setting mechanism,

Fig. 10 shows in a view similar to Fig. 1 to an enlarged scale the string feeding devices in their string feeding position, and their relation to the punching and eyelet setting mechanism, this view being taken along the line 10—10 in Fig. 2,

Fig. 11 is a sectional view to an enlarged scale of the punching and eyelet setting mechanism used in connection with the eyelet and washer used to secure the string to the envelope, this view being taken in the plane indicated by the right hand portion of the broken line 10—10 in Fig. 2,

Fig. 12 is a top view of part of the mechanism shown in Fig. 11,

Fig. 13 is a side elevation of the string delivery device,

Fig. 14 is a sectional view of the parts shown in Fig. 13 taken along the line 14—14, and

Fig. 15 is a detail view of the lower end of the eyelet guide employed to feed the eyelets to the mechanism shown in Figs. 11 and 12.

Similar numerals refer to similar parts throughout the several views.

As shown in Figs. 1 and 2 my machine consists of a base 20 on which an operating shaft 21 is mounted in suitable bearings to extend throughout the length of the machine and on this shaft a driving wheel 22 is mounted for free rotation excepting only when the clutch mechanism 23 is operated by the treadle 24 through the communicating devices 25, at which time the driving wheel is connected to the shaft 21 and moves the same through one rotation at the end of which the clutch mechanism 23 disengages the driving wheel and stops the operation of the main shaft, assuming that the treadle 24 is released by the operator immediately after the operation of the same. The shaft 21 is provided with a hand wheel 26 for rotating the shaft manually in setting up the machine.

The base 20 carries on its left hand portion punches 27 and 28 as seen in Fig. 2, below each of which a perforating punch is located as indicated at 29 in Fig. 1, for the punch 27, the punch 29 serving to perforate the corresponding washer strip below the punch 27 after which the washer strip is fed upwardly as will be described in line with the punch 27 which cuts the washer from the strip and at the same time engages an eyelet and secures the washer to the body portion of the envelope, the eyelets being fed into line with the punch 27 by the eyelet guide 30. The punch 28 and its perforating punch similarly operate on a second washer strip with the exception that the punch 28 does not carry eyelets, but serves merely as a setting punch for the eyelets supplied to the flaps of the envelopes by the punching mechanism on the other side of the machine. The punches 27 and 28 have secured to them, operating heads 31 and 32 which also engage the corresponding perforating punches referred to and these heads are connected together by a rod 33 engaged by a link 34 pivotally connected with the crank 35 carried by a shaft 36 mounted in a suitable bearing on the base 20. The other end of the shaft 36 has secured thereto a bevel gear 37 meshing with a similar bevel gear 38 secured to the shaft 21. The head 31 is adjustable on the rod 33 as is also the guide 39 on the base 20, provided for the punches 27 and 29, to allow different spacings between the eyelets attached to the body portion of the envelope and the eyelets attached to the flaps of the envelopes.

The base 20 also carries in suitable sup-

135

ports a punch 40 as shown in Fig. 2 for punching washers from a washer strip and carrying eyelets to the flap portion of the envelope after the closing strings have been 5 inserted in and retained by said washers. Below the punch 40 as shown in Fig. 1, a perforating punch 42 is located, which punches are connected by a head 43 having in its rear face a vertical guide 44 engaged 10 by a roller 45 carried by the end of the crank 46 secured to a shaft 47 supported in a bearing 48 mounted on the base 20. The other end of the shaft 47 has rigidly secured thereto a bevel gear 49 meshing with a similar bevel gear 50 secured to the shaft 21. The bevel gears and cranks are so proportioned that one rotation of the shaft 21 moves all of said punches from their outermost position through their complete cycle 20 of operation.

Vertical guideways 51 and 52 are provided in line with the punches 27 and 40 to lead washer strips 53 and 54 from supply reels 55 and 56 respectively, mounted under 25 the base 20 to the feeding rollers 57 and 58 carried by suitable brackets above the base. A similar vertical guideway 59 is provided in line with the punch 28 for receiving a washer strip from a reel identical 30 with the reel 55 immediately behind it and this washer strip is engaged at its upper end by feeding rollers 60. The feeding rollers 57 and 60 are connected together for simultaneous operation by a suitable shaft 35 64 and this shaft is extended to carry a ratchet wheel 61 engaged by a pawl 62 carried by a swinging arm 63 mounted on the shaft 64 carrying said ratchet wheel, said arm being connected by a link 65 engaging 40 and actuated by a cam 66 secured to the shaft 36 so that each complete rotation of the shaft 36 causes a single operation of the link 65 and advances the feeding rolls 57 and 60 somewhat more than the diameter of the washers punched from the washer strips 45 so that the strips after the washers are punched therefrom shall have sufficient strength to feed the blank portion of the strips through the guideways referred to. A spring 67 serves to hold a roller 68 carried by the link 65 in engagement with the cam 66. The feeding rollers 58 are similarly operated by a cam 69 carried by the shaft 47. Knobs 70 and 71 are connected 55 with the roller feeding shafts to permit operation of the rollers manually in setting up the machine.

Eyelets are supplied to the punches 27 and 40 respectively by eyelet guides 30 and 72 which are supplied from hoppers not shown, as they are well known in the art and these hoppers have connected with them rods 73 and 74 actuated by cams 75 and 76 respectively, carried by and secured to the shaft 21, said rods operating in a well

known manner, not shown, to facilitate delivery of eyelets from said hoppers to said eyelet guides. The eyelet guides are also provided with delivering mechanism actuated by rods 77 and 78 from cams 79 and 80 respectively, carried by and secured to the shaft 21, each of these rods serving in a manner to be described to deliver one eyelet at a time to the lower end of the eyelet guide in the path of the corresponding 75 punch.

An anvil plate 81 is supported by the base 20, with a clearance between it and the dies cooperating with the punches 27 and 29, to receive the body portion of the envelope so that the punch 27 by its operation engages an eyelet in the guide 30 and carries it with a washer cut from the washer strip in the guide 51 to the body of the envelope through which the eyelet is forced by the punch against a setting die 82 carried by the anvil. A clearance is left between the anvil plate 81 and the dies cooperating with the punches 40 and 42 to receive the flap of the envelope in extended relation and also to permit the string feeding devices to be moved adjacent and into the die cooperating with the punch 40 to feed the string, in a manner to be described, 85 through an aperture in the washer strip in the guide 52 at that time in line with the punch 40. The string feeding devices are carried by an arm 83 secured to a shaft 84 carried by the upper end of a bracket 85 mounted on the base 20 and to the other end of said shaft, an arm 86 is secured, pivotally connected to a link 87 which at its lower end carries a roller 88 resting on a cam 89, said cam being mounted upon and secured to the shaft 21. The shaft 21 also carries a cam 90 which is rigidly secured thereto for actuating a bar 91 which in turn operates the gripper provided for retaining the string fed through the washer aperture in a manner to be described. The shaft 21 also carries a cam 92 which is rigidly secured to said shaft, which operates a rock shaft 93 connected in turn to a rod 94, which, after the arm 83 is in string feeding 90 position, actuates the feeding mechanism on the arm to feed the string through the washer aperture. The shaft 21 also carries a cam 95 which is rigidly secured thereto, to actuate the string cutting mechanism 96 when the arm 83 is in its retracted position. 95

The string feeding and handling devices are shown more clearly in Figs. 3 to 8 and 13 and 14 to which reference is now made. As shown in Fig. 3 the arm 83 carries at its lower end and pivoted thereto, a string guide 97, the pivot rod 98 of which projects upwardly and carries a projecting arm 99 which, as the arm 83 is moved to bring the nose of the guide 97 opposite the opening 100 110 115 120 125 130

100 in the die in line with the punch 40, engages a stop bar 101 carried by a plate 102 extending upwardly from the base 20; further movement of the arm 83 to bring it into engagement with its motion limiting stop 103, adjustably secured to the plate 102 as indicated, turns the guide 97 so that its nose is moved into the opening 100 and the gear 104, later described, is brought 10 into mesh with the rack 105 mounted to slide in guides 106 carried by the plate 102. At the instant this relation is secured, the roller 88 engages a delay surface on the cam 89 and the rack 105 is actuated by the 15 mechanism shown in Fig. 5. This consists of a lever 107 pivotally supported on the plate 102 at 108, one end of which is pivotally connected at 109 with the rack 105 and the other end of which is connected with one 20 end of a link 94 the other end of which is pivotally connected with an arm 110 carried by the rock shaft 93, which carries a second arm 111 to which a roller 112 is secured resting upon the surface of the cam 92. A 25 spring 113 is provided between the plate 102 and the link 94 to move the rack 105 to the left as shown in Fig. 5, when the cam 92 is in position to permit such motion. This occurs only during the interval that the arm 30 83 is held against its stop 103. In this manner the string is fed from the guide 97 through a washer aperture in line with the nose of said guide.

The detail construction of the spring 35 guide is more clearly shown in Figs. 13 and 14 in which the guide 97 is shown mounted on and rigidly secured to the rod 98 pivoted in the forked lower end of the arm 83. The 40 guide consists of two parts 97^a and 97^b pivoted together by means of a rod 114 and said parts carry respectively shafts or rods 115 and 116, to which are secured in the recess formed therefor in said parts, feeding rollers 117 and 118 respectively. Said 45 rods extend above the parts of the string guide and have secured to their upper ends gears 104 and 104^a respectively which mesh with each other, the gear 104 being the one brought into mesh with the rack 105 50 by the operation above described. The part 97^b is provided with a guiding passageway 119 for directing the string to the feeding rollers 117 and 118 which, as indicated in Fig. 13 are preferably grooved slightly and 55 roughened or knurled to firmly engage the string. A spring 120 holds the outer ends of the parts 97^a and 97^b together so that the feeding rollers nearly or quite engage each other and when the string is to be inserted 60 between the feeding rollers, the rollers may be separated slightly by pressure on the part 97^b opposite the spring 120, which spring also provides an engagement between the feeding rollers and the string permitting 65 irregularities in the string to pass through

the feeding rollers without jamming the string or interfering with the operation of the devices employed to rotate the feeding rollers. A delivery passage 121 extends from the feeding rollers through the part 70 97^a to the nose of the string guide which as indicated is preferably tapered and pointed to clear the edge of the opening 100 shown in Fig. 3. A clearance 100^a is preferably cut in the edge of the opening 75 100 to more readily permit the nose of the string guide to enter the opening 100.

As shown in Fig. 3, the lower end of the rod 87 carries a forked guide 87^a which passes around the shaft 21 to maintain the rod and roller 88 carried thereby in proper relation to the cam 89. The rod 65 shown in Fig. 2 for operating the feeding rollers 57 and 60, and the similar rod employed for operating the feeding rollers 58 are 80 preferably similarly constructed to engage the shafts 36 and 47 respectively to hold the rollers carried by said rods in proper engagement with the cams 66 and 69 respectively. As shown in Fig. 3, a spring 122 is 85 provided between the base 20 and the upper end of the rod 87 to hold the roller 88 in engagement with the surface of the cam 89, said spring serving to move the arm 83 into its string feeding position when the position of the cam 89 permits said motion, motion in the opposite direction of the arm being effected positively by the cam 89. As also 90 shown in Fig. 3, a spring 123 is provided 95 between a lug carried by the arm 99 and the arm 83 to hold the guide 97 substantially parallel with the plate 102 when the arm 99 is not in engagement with the stop 101. The string preferably extends from the passageway 119 shown in Figs. 13 and 14 upwardly 100 along the arm 83, to which, if desired, it may loosely be held by any suitable guides and from which it extends to a supply spool 105 or roll not shown.

After the string has been fed through a 110 washer aperture in the guide 52 by the devices above described the projecting end of the string is engaged by the gripper construction shown in Fig. 4. This consists of a pair of jaws 124 and 125 pivotally supported on a stud 126 projecting from the plate 102, so that in their open position they clear the openings 100 and 127 in line with the punches 40 and 42. The jaws are in the 115 form of bell crank levers having arms projecting above and below the stud 126, the ends of said arms being connected by links 128 and 129 with the end of the operating rod 91 mounted to slide horizontally in a suitable guide 130. Springs 131 and 132 are connected between said links and said guide to move the rod 91 outwardly and the jaws 124 and 125 together, when the surface 120 of the operating cam permits this motion. It will be understood that the action of the 125 130

jaws 124 and 125 must be accurately timed and that their gripping action is but momentary; to secure this I preferably construct the cam 90 in two parts 90^a and 90^b secured together by screws 90^c extending through slots in one of the parts of the cam 90. As indicated in Fig. 7 one of the parts, as for example part 90^b of the cam, is provided with a hub 90^d by which the cam may be secured by a suitable set screw in desired position on the shaft 21 and the other part 90^a of the cam receives its support from said hub 90^d. One of the operating faces of the cam is preferably carried by each of the parts thereof as a result of which the exact interval of operation of the gripping devices may be determined to a nicety and the action of the cam as a whole relatively to the other devices controlled by the shaft 21, 20 may be secured by properly locating the cam as a whole on the shaft.

The operation of the punching mechanism and the timing of the several operations will best be understood by reference to Figs. 9 and 10. After the envelope has been placed on the anvil bar 81 with its body portion adjacent the die 82, and the clutch 23 connected with the shaft 21 has been released to start the machine in operation, movement 30 of the punches on both sides of the envelope is begun towards the envelope and the several washer strips are fed by their cam actuating mechanism described above, to bring the perforations formed in said strips by the preceding operation, in line with the axes of the punches that punch the washers from the strips. At the same time, the arm 83 is advanced from its position of rest, indicated by the dotted lines in Fig. 3, to the position 35 indicated in Fig. 9 in which position the arm 99 has engaged the stop 101 and turned the string guide 97 so that its nose enters the aperture 100 extending through the plate 102 and the die 133 cooperating with the punch 40. At this time it will be understood the washer strip is in the guideway 52 but for the sake of clearness, the strip is omitted from Fig. 9 as are the other washer strips employed. By the operation of the rod 78 an eyelet has been delivered to the lower end of the eyelet guide 72, in line with the axis of the punch 40 in a manner to be described, in readiness to be removed from the eyelet guide and carried by the punch 40 into the said perforation in the washer strip immediately before the washer is punched from the strip, but before the punch 40 has been advanced sufficiently to do this, the string is fed through the perforation in 45 the washer strip by operation of the rack 105 as above described. Immediately upon the string being fed through the perforation in the washer strip and through the wall of the guideway 52, the gripper jaws 124 and 125 are brought together by the springs connect-

ed with them in the manner above described, to securely engage the end of the string 134. Immediately upon this occurring, the arm 83 moves quickly away from the position indicated in Fig. 9, sufficiently to permit the string guide 97 to move into a plane parallel with the plate 102 and so that the nose of the string guide is in a position just back of the path of the punch 40. In this position the arm 83 is held momentarily by a delay surface on its actuating cam, the gripping jaws 124 and 125 are immediately opened and the punch 40 and parts carried thereby advance to engage the lowermost eyelet 125 in the guideway 72 and move it firmly into the perforation in the washer strip immediately before the punch 40 punches the washer from the strip. The perforation in the washer strip is a close fit for the eyelet as a result of which the string 85 is jammed between the eyelet and the edge of the perforation and held securely enough to insure it being retained against the action of drawing the string through the guide 97 and whatever other string guides are employed, as the arm 83 is moved away from its string feeding position. Immediately upon the string being engaged in the washer strip as described, a further backward movement of the arm 83 begins and the punch 40 90 continues its forward movement after punching the washer from the strip and moves the washer and the attached eyelet and string towards the flap of the envelope not shown, while at the same time the punch 28 is advanced to punch the washer from the strip 53^a in the guideway 59, said washer being held on the end of said punch by the center rounded projection 28^a used subsequently to receive the end of the eyelet 100 135 to set the same after it has been forced through the envelope when the punches 28 and 40 have been brought firmly together in the space between the plate 102 and the anvil plate 81. The setting operation referred to 105 forces the eyelet through the washer carried by the punch 28 and thus securely holds the two washers on either side of the flap of the envelope with the string securely clamped between the eyelet and washer on the outer 110 surface of the flap and the end of the string projecting slightly beyond the eyelet on the outer surface of the washer, the main portion of the string extending from the eyelet between the washer and the outer surface of 115 the flap of the envelope.

During the setting of the eyelet in the manner above described, the punch 27 has been advanced so that its punch rod 27^a has removed an eyelet from the eyelet guideway 125 30 in the same manner described above for the eyelet 135 and continued motion of the punch 27 has forced the eyelet through a washer perforation in the washer strip contained in the guideway 51 and immediately 130

thereafter the punch has punched a washer from said strip and carried the washer and eyelet against the body portion of the envelope to force the eyelet through the envelope and against the setting die 82, the setting of the eyelet occurring at the same time that the eyelet 135 is set by the punches 28 and 40.

At the same time that the eyelets have been set in the envelope in the manner described the arm 83 has reached its fully retracted position, in doing which it passes just beyond the string cutting mechanism 96 and this is immediately operated as will best be understood by reference to Figs. 6 and 8. The string cutting devices 96 as shown in Figs. 6 and 8 consist of the guide 136 mounted in inclined position on the base 20 to support a sliding bar 137 from which a stud 138 projects outwardly to form the pivotal support for two shear blades 139, 139 in the form of bell crank levers which are pivotally connected by links 140, 140 with a fixed stud 141 extending from the guide 136. The bar 137 is provided with a laterally extending lug 142 adjacent the surface of the cam 97 to be engaged by an operating lug 97^a projecting from the outer surface of the cam. A spring 143 has its ends connected to the studs 138 and 141 and tends to hold the bar 137 in its lowermost position in the guide 136, for which position the shear blades 139 occupy the position indicated in Fig. 8. The slide 137 is prevented from moving beyond the position indicated in Fig. 6 by an enlarged head 144 carried on the upper end of the slide, which engages the upper end of the guide 136 for the lowermost position of the sliding bar, from which head the lug 142 projects. A spring 145 is mounted on the stud 138 and presses against the outermost shear blade 139 to hold the shear blades together with sufficient pressure to insure a positive cutting of the string. Immediately upon the arm 83 reaching its extreme rear position for which the nose of the string guide is just back of the shear blades, the lug 97^a engages the lug 142 and the slide 137 is raised bringing the shear blades together and since the string extending from the string guide to the envelope lies between the shear blades when they are raised, it is severed when they are brought together. The operation of the shear blades occurs at substantially the same time that the envelope is released by backward movement of the several punches and the envelope may therefore be removed from the machine as soon as it is released by the punches. The interval required for the operation of the shear blades is brief and is terminated as soon as the lug 97^a passes under the lug 142 on account of the increasing distance between the lugs as the cam 97 rotates and when said lugs are disengaged the spring

143 immediately moves the shear blades to their open position shown in Fig. 8. All of the parts are placed in readiness for a repetition of the operation described, as soon as the punches reach their retracted position at 70 which time the clutch mechanism 23 engages the shaft 21 and prevents rotation of the shaft until the clutch mechanism is again released.

It will be noted as indicated in Figs. 2 75 and 9 that the die plate 82 is mounted in a clearance opening in the anvil plate 81 which permits movement of the die plate towards or away from the punch 28 as required to secure different distances between 80 the eyelets in the flap and in the body portions of the envelope, the punches 27 and 29 being similarly adjustable on the base 20 as above described.

To insure proper operation of the punch 85 40 to effect the various operations described I prefer to construct the punch as shown in Figs. 11 and 12. The punch as shown in these figures, is in the form of a tube throughout the greater portion of its length, 90 which tube contains a rod 40^a of smaller diameter than the bore of the tubular portion and which extends through the working end of the punch with a sliding fit, its diameter being such that it is also a sliding 95 fit in the eyelets used in the machine. The rod 40^a is secured at its inner end to a plunger 146 which is a sliding fit in the bore of the tubular portion of the punch 40 and from the other end of which a second rod 100 40^b, similar to the rod 40^a, extends through a screw plug 40^c screwed into the outer end of the punch 40, said rod 40^b having at its outer end an enlarged head 40^d to engage a bumper 40^e when the plunger 146 is released. 105 The head 40^d also provides for setting the plunger in its operating position in the punch 40, if desired in connection with setting up the machine. A spring 147 is contained in the punch 40 around the rod 40^b 110 between the plunger 146 and the plug 40^c to move the rod 40^a quickly through the eyelet to be operated upon, when the plunger 146 is released. A latch 148 is pivotally connected at 149 to the tubular portion of 115 the punch 40 so that in the position it naturally assumes by gravity it engages the end of the plunger 146 to hold it in a position compressing the spring 147. The latch is provided with a projecting pin 150 at its 120 free end for engaging a cam 151 after the punch has been advanced somewhat on its forward stroke, the cam serving to lift the latch and disengage the plunger 146 at which time the spring 147 forces the rod 125 40^a quickly through the eyelet in line therewith and also through the perforation in the washer strip after the string has been fed therethrough in the manner described. When the punches have been advanced to 130

set the eyelet, the spring 147 is compressed by the engagement between the outer end of the rod 40^a and the punch 28 for which condition the latch 148 drops into the path 5 of the plunger 146 to hold it in a position compressing the spring 147. The cam 151 as indicated in Fig. 12 is provided with an inclined lateral surface 151^a and the cam is supported in the path of the pin 150 by 10 a flexible leaf spring 152 permitting lateral movement of the cam when the pin 150 engages the inclined surface 151^a and this permits the punch 40 to move to its rear or retracted position although the pin 150 15 is in the path of the cam 151. The cam 151 is preferably secured to the base 20 in a manner as indicated at 153 permitting adjustment of the cam longitudinally of the punch to effect the release of the plunger 20 146 at the precise moment desired. The relation of the punch 42 to the punch 40 is also shown in Fig. 11 and it will be noted that the end of the said punch is of reduced diameter to perforate the washer strip in 25 the guide-way 52 below the position of punching the washer itself from the strip, the amount of motion imparted to the strip as described above being equal to the distance between the axes of the punches 42 30 and 40 for each cycle of operation of the punches.

The punch 27, as shown in Figs. 1 and 10, is also provided with a spring actuated plunger rod 27^a, similar to the rod 40^a described for the punch 40, but in this case no accurate timing of the plunger rod is required since the purpose of the rod 27^a is to engage the lowermost eyelet in the eyelet guide 30 and carry it through the washer 40 perforation in the strip in the guideway 51 and to retain the eyelet and washer after it is punched, in proper position on the end of the punch 27 until the eyelet is moved into engagement with the die plate 82, at 45 which time the plunger rod 27^a yields to permit the punch 27 to firmly press and set the eyelet against the die plate.

The devices employed for controlling the eyelet feed are shown in detail in Fig. 15 50 for the guideway 72, it being understood that the guideway 30 is of similar construction and provided with similar feeding devices. The bar 78 is extended beyond the slot in the guideway 72 and is provided 55 with projecting lugs 78^a and 78^b projecting from the upper and lower edges of the bar 78 in staggered relation so that motion of the bar 78 in one direction brings the upper lug 78^a in engagement with an eyelet in the 60 guideway and motion in the reverse direction releases the eyelet and permits it to drop upon the lug 78^b for which condition the eyelets in the upper part of the guideway move downward an amount equal to 65 the diameter of one eyelet. The lugs 78^a

and 78^b are displaced relatively to the path of travel of the eyelets, as a result of which when the bar 78 is again moved to disengage the lug 78^b from the eyelet resting upon it, the lug 78^a engages the eyelet immediately above it and the released eyelet descends in the guideway 72 to clearances formed to receive it in two retaining doors 154 and 155 pivotally supported on the lower end of the guideway at 156 and 157, said 70 doors being held in eyelet receiving position by springs 158 and 159 respectively. The eyelet supported by the doors 154 and 155 is in line with the axis of the punch 40 and the doors are of a size to be pushed aside by 75 the punch as it passes the lower end of the guideway after the rod 40^a has engaged the eyelet supported by the doors to hold it in position to be moved through the washer by 80 the punch 40 in the manner above described. 85

From the above description it will be noted that no tension or stress is placed upon the string in placing it in position to be engaged by the eyelet and retaining washer and that the only strain exerted on 90 the string at any time is that required to move it through the various guiding devices and from the reel or spool. On the other hand the string is positively fed to correct position to be engaged and clamped by the 95 washer, before any clamping action is exerted upon the string after which the string is engaged and secured between the eyelet and the edge of a washer perforation in the washer strip before the washer is formed, 100 after which the string is securely clamped between the washer and the outer face of the flap of the envelope by the setting of the eyelet. As a result of securing the string in this manner, the string extends outwards 105 radially of the washer on both sides thereof and is held so securely by the clamping action that it cannot be pulled out without tearing the washer.

While I have shown my invention in the 110 particular embodiment above described, it will be understood that I do not limit myself to this exact construction but that I may employ equivalents known to the art at the time of the filing of this application 115 without departing from the scope of the appended claims.

What I claim is:

1. String feeding mechanism for machines for securing washers and strings to envelopes having means for supporting an envelope and a perforated washer blank at a distance from each other as a part of such machine, consisting of mechanism movable between and away from the spaced envelope and washer blank to feed a string through the perforation in a washer blank. 120

2. String feeding mechanism for machines for securing washers and strings to envelopes having means for supporting an envelope 125

- and a perforated washer blank at a distance from each other as a part of such machine, consisting of mechanism movable between and away from the spaced envelope and washer blank to feed a string through the perforation in a washer blank, said mechanism comprising a member having cyclic motion, and string feeding devices carried by the delivery portion of said member.
- 10 3. String feeding mechanism for machines for securing washers and strings to envelopes having means for supporting an envelope and a perforated washer blank at a distance from each other as a part of such machine, consisting of mechanism movable between and away from the spaced envelope and washer blank to feed a string through the perforation in a washer blank, said mechanism comprising a member having cyclic motion, and feeding rollers carried by the delivery portion of said member.
- 15 4. String feeding mechanism for machines for securing washers and strings to envelopes having means for supporting an envelope and a perforated washer blank at a distance from each other as a part of such machine, consisting of mechanism movable between and away from the spaced envelope and washer blank to feed a string through the perforation in a washer blank, said mechanism comprising a member having cyclic motion, feeding rollers carried by the delivery portion of said member, gears secured to said rollers, and a movable rack for operating said gears.
- 20 5. String feeding mechanism for machines for securing washers and strings to envelopes having means for supporting an envelope and a perforated washer blank at a distance from each other as a part of such machine, consisting of mechanism movable between and away from the spaced envelope and washer blank to feed a string through the perforation in a washer blank, said mechanism comprising a member having cyclic motion, feeding rollers carried by the delivery portion of said member, gears secured to said rollers, a movable rack for operating said gears, a cam, and operating connections between said cam and rack.
- 25 6. String feeding mechanism for machines for securing washers and strings to envelopes having means for supporting an envelope and a perforated washer blank at a distance from each other as a part of such machine, consisting of mechanism movable between and away from the spaced envelope and washer blank to feed a string through the perforation in a washer blank, said mechanism comprising a member having cyclic motion in a first direction, a string delivering device carried by said member and movable relatively thereto to present the end of the string to the perforation in a washer blank, and feeding rollers carried by said delivering device.
- 30 7. String feeding mechanism for machines for securing washers and strings to envelopes having means for supporting an envelope and a perforated washer blank at a distance from each other as a part of such machine, consisting of mechanism movable between and away from the spaced envelope and washer blank to feed a string through the perforation in a washer blank, said mechanism comprising a member having cyclic motion in a first direction, a string delivering device carried by said member and movable relatively thereto to present the end of the string to the perforation in a washer blank, and feeding rollers carried by said delivering device.
- 35 8. String feeding mechanism for machines for securing washers and strings to envelopes having means for supporting an envelope and a perforated washer blank at a distance from each other as a part of such machine, consisting of mechanism movable between and away from the spaced envelope and washer blank to feed a string through the perforation in a washer blank, said mechanism comprising a member having cyclic motion in a first direction, a string delivering device carried by said member and movable relatively thereto to present the end of the string to the perforation in a washer blank, feeding rollers carried by said delivering device, gears secured to said rollers, and a movable rack for operating said gears.
- 40 9. String feeding mechanism for machines for securing washers and strings to envelopes having means for supporting an envelope and a perforated washer blank at a distance from each other as a part of such machine, consisting of mechanism movable between and away from the spaced envelope and washer blank to feed a string through the perforation in a washer blank, said mechanism comprising a member having cyclic motion in a first direction, a string delivering device carried by said member and movable relatively thereto to present the end of the string to the perforation in a washer blank, feeding rollers carried by said delivering device, gears secured to said rollers, a movable rack for operating said gears, a cam, and operating connections between said cam and rack, movement of said delivering device relatively to said member moving one of said gears into or from the path of said rack.
- 45 10. String feeding mechanism for machines for securing eyelets, perforated washers and strings to envelopes, comprising a string carrying member having cyclic motion, and feeding rollers for feeding a string relatively to said member through a

- washer perforation independently of and before connection of said string to any of said eyelets, washers or envelopes.
11. String feeding mechanism for machines for securing eyelets, perforated washers and strings to envelopes, comprising a string carrying member having cyclic motion, feeding rollers for feeding a string relatively to said member through a washer perforation independently of and before connection of said string to any of said eyelets, washers or envelopes, gears secured to said rollers, and a movable rack for operating said gears.
12. String feeding mechanism for machines for securing eyelets, perforated washers and strings to envelopes, comprising a string carrying member having cyclic motion, feeding rollers for feeding a string relatively to said member through a washer perforation independently of and before connection of said string to any of said eyelets, washers or envelopes, gears secured to said rollers, a movable rack for operating said gears, a cam, and operating connections between said cam and rack, movement of said delivering device relatively to said member moving one of said gears into or from the path of said rack.
13. String feeding mechanism for machines for securing eyelets, perforated washers and strings to envelopes, comprising a string carrying member having cyclic motion in a first direction, a string delivering device carried by said member and movable relatively thereto to present the end of the string to the perforation in a washer, and feeding devices for feeding a string relatively to said string delivering device through a washer perforation independently of and before connection of said string to any of said eyelets, washers or envelopes.
14. String feeding mechanism for machines for securing eyelets, perforated washers and strings to envelopes, comprising a string carrying member having cyclic motion in a first direction, a string delivering device carried by said member and movable relatively thereto to present the end of the string to the perforation in a washer, and feeding rollers for feeding a string relatively to said string delivering device through a washer perforation independently of and before connection of said string to any of said eyelets, washers or envelopes.
15. String feeding mechanism for machines for securing eyelets, perforated washers and strings to envelopes, comprising a string carrying member having cyclic motion in a first direction, a string delivering device carried by said member and movable relatively thereto to present the end of the string to the perforation in a washer, feeding rollers for feeding a string relatively to said string delivering device through a washer perforation independently of and before connection of said string to any of said eyelets, washers or envelopes,
16. String feeding mechanism for machines for securing eyelets, perforated washers and strings to envelopes, comprising a string carrying member having cyclic motion in a first direction, a string delivering device carried by said member and movable relatively thereto to present the end of the string to the perforation in a washer, feeding rollers for feeding a string relatively to said string delivering device through a washer perforation independently of and before connection of said string to any of said eyelets, washers or envelopes, gears secured to said rollers, and a movable rack for operating said gears.
17. String feeding mechanism for machines for securing eyelets, perforated washers and strings to envelopes, comprising an oscillatory arm, and string feeding devices carried by said arm for moving a string relatively to said arm.
18. String feeding mechanism for machines for securing eyelets, perforated washers and strings to envelopes, comprising an oscillatory arm, string feeding rollers carried by said arm, and devices for rotating said rollers.
19. String feeding mechanism for machines for securing eyelets, perforated washers and strings to envelopes, comprising an oscillatory arm, a string delivering device carried by said arm and movable relatively thereto, and string feeding devices carried by said delivering device.
20. String feeding mechanism for machines for securing eyelets, perforated washers and strings to envelopes, comprising an oscillatory arm, a string delivering device carried by said arm and movable relatively thereto, feeding rollers carried by said device, and means for operating said rollers.
21. String feeding mechanism for machines for securing eyelets, perforated washers and strings to envelopes, comprising an oscillatory arm, a string delivering device carried by said arm and movable relatively thereto, feeding rollers carried by said device, gears secured to said rollers, a rack for operating said gears, a cam, and operating connections between said cam and rack.
22. String feeding mechanism for machines for securing eyelets, perforated washers and strings to envelopes, comprising a member having cyclic motion, a string delivering device carried by said member and movable relatively thereto to present the end of a string to the perforation in a washer, feeding rollers carried by said de-

- livering device, and a gripper for holding the string end projecting through the washer perforation to permit movement of said string feeding mechanism from its feeding position.
23. String feeding mechanism for machines for securing eyelets, perforated washers and strings to envelopes, comprising string feeding mechanism for feeding a string end through a washer perforation, a gripper for holding the string end projecting through the washer perforation to permit movement of said string feeding mechanism from its feeding position, and shearing mechanism for cutting the string adjacent to string feeding mechanism.
24. In a machine of the class described, string feeding mechanism comprising a member having cyclic motion, and feeding rollers adjacent and carried by its delivery end for feeding a string.
25. In a machine of the class described, string feeding mechanism for feeding a string through a washer perforation, said string feeding mechanism comprising a member having cyclic motion, feeding rollers adjacent and carried by its delivery end for feeding a string, gears secured to said rollers, and a movable rack for operating said gears.
26. In a machine of the class described, string feeding mechanism for feeding a string through a washer perforation, said string feeding mechanism comprising a member having cyclic motion, feeding rollers adjacent and carried by its delivery end for feeding a string, gears secured to said rollers, a movable rack for operating said gears, a cam, and operating connections between said cam and rack.
27. In a machine of the class described, string feeding mechanism for feeding a string through a washer perforation, said string feeding mechanism comprising a member having cyclic motion, a string delivering device carried by said member and movable relatively thereto to present the end of the string to a perforation in a washer, and feeding devices carried by said delivering device.
28. In a machine of the class described, string feeding mechanism for feeding a string through a washer perforation, said string feeding mechanism comprising a member having cyclic motion, a string delivering device carried by said member and movable relatively thereto to present the end of the string to a perforation in a washer, and feeding rollers carried by said delivering device.
29. In a machine of the class described, string feeding mechanism for feeding a string through a washer perforation, said string feeding mechanism comprising a member having cyclic motion, a string de-
- livering device carried by said member and movable relatively thereto to present the end of the string to a perforation in a washer, feeding rollers carried by said delivering device, gears secured to said rollers, and a movable rack for operating said gears.
30. In a machine of the class described, string feeding mechanism for feeding a string through a washer perforation, said string feeding mechanism comprising a member having cyclic motion, a string delivering device carried by said member and movable relatively thereto to present the end of the string to a perforation in a washer, feeding rollers carried by said delivering device, gears secured to said rollers, a movable rack for operating said gears, a cam, and operating connections between said cam and rack, movement of said delivering device relatively to said member moving one of said gears into or from the path of said rack.
31. In a machine of the class described, string feeding mechanism for feeding a string through a washer perforation, said string feeding mechanism comprising an oscillatory arm, and string feeding devices carried by the delivery end of said arm.
32. In a machine of the class described, string feeding mechanism for feeding a string through a washer perforation, said string feeding mechanism comprising an oscillatory arm, and string feeding rollers carried by the delivery end of said arm.
33. In a machine of the class described, the combination of string feeding mechanism for feeding a string end through a washer perforation, and a gripper for holding the string end projecting through the washer perforation to permit movement of said string feeding mechanism from its feeding position.
34. In a machine of the class described, the combination of string feeding mechanism for feeding a string end through a washer perforation, and a gripper for holding the string end projecting through the washer perforation to permit movement of said string feeding mechanism from its feeding position, said gripper comprising two jaws pivotally supported, and springs tending to move said jaws together.
35. In a machine of the class described, the combination of string feeding mechanism for feeding a string end through a washer perforation, and a gripper for holding the string end projecting through the washer perforation to permit movement of said string feeding mechanism from its feeding position, said gripper comprising two jaws pivotally supported, and springs tending to move said jaws together, a cam, and connections between said cam and said jaws releasing said jaws after said string is fed through the washer perforation and

opening said jaws when the string feeding mechanism is moved backward away from the washer.

36. In a machine of the class described, the combination of string feeding mechanism for feeding a string through a washer perforation, a gripper for holding the string projecting through a washer perforation to permit movement of said string feeding mechanism from its feeding position, and shearing mechanism for cutting the string adjacent the string feeding mechanism, said shearing mechanism comprising shear blades, a slide carrying said blades, a fixed support, connections extending from said blades to said fixed support for operating said blades by movement of said slide, a spring tending to hold said slide in position opening said blades, and a cam having a lug extending into the path of said slide to operate said slide and blades.

37. In a machine of the class described, the combination of string feeding mecha-

nism movable between and away from a perforated washer and envelope to feed a string through a washer perforation, a gripper for holding the end of said string during motion of said string feeding mechanism away from its feeding position, and shearing mechanism for cutting the string adjacent the string feeding mechanism in its retracted position, said shearing mechanism comprising shear blades, a slide carrying said blades, a fixed support, connections extending from said blades to said fixed support for operating said blades by movement of said slide, a spring tending to hold said slide in position opening said blades, and a cam having a lug extending into the path of said slide to operate said slide and blades.

In witness whereof, I hereunto subscribe my name this 28th day of February, A. D. 1922.

STANLEY B. URBANOWITZ.
